UNITED STATES PATENT OFFICE

JAMES C. HOBBS, OF PAINESVILLE, OHIO

FURNACE WALL

Application filed June 17, 1925. Serial No. 37,638.

My invention more particularly relates to a furnace wall provided with means for increasing the rate of heat transmission through the wall from the furnace side, and thereby increasing the life of the wall or permitting higher furnace temperatures and resulting economy or both.

Other features of my invention will be apparent from the specification and will be particularly pointed out in the claims.

My invention will best be understood by reference to the accompanying drawings, in which I have illustrated one embodiment thereof and in which Fig. 1 is a vertical section through a furnace embodying my invention and illustrating a portion of the boiler located above the same; Fig. 2 is a fragmentary sectional view illustrating a portion of Fig. 1 and taken along the line 2—2 of Fig. 20 3, looking in the direction of the arrows, and Fig. 3 is a section taken along the line 3—3 of Fig. 2 looking in the direction of the arrows.

Like reference characters indicate like parts throughout the drawings.

Referring to the drawings, 10 and 11 are the front and rear walls, respectively, of a furnace, the inside face of one of the side walls being indicated at 12. The furnace 30 is fired by any suitable fuel, in the embodiment illustrated by powdered fuel, the burner for which is indicated at 13. In the form shown, the nozzle 13 extends through an opening 14, in a suitable roof or arch 15 35 located at the upper front portion of the furnace, having an upwardly extending portion 16. An auxiliary wall 17 is supported upon and extends upwardly from the rear wall 11, a suitable boiler being located above 40 the furnace, a portion of the tubes of which boiler are indicated at 18, and which are connected at their ends to a downtime header 19 and an uptake header 20.

In the form shown, a heat insulating casting 45 21 is spaced from the front wall 10. The rear wall of the furnace, in the embodiment illustrated, comprises two spaced sections 11^a and 11^b, which are preferably connected together by bonding tiles 11^c.

In accordance with my invention, mem-

bers of good heat conducting material, as compared with the refractory members with which the wall is formed, are placed in the inner section 11 of the wall and extend outwardly therefrom. In the form shown, 55 these members 22 consist of a metallic plate or plates, formed of a good heat conducting material, such as copper, which are laid between the tiles 111 of the section 11^a of the wall, and are preferably spaced at their inner ends somewhat from the inner face of the wall, as at 23, in order to protect the ends of the members from the heat of the furnace. The space 23 between the ends of the members 22 and the inner face of the wall 35 is filled in with suitable clay or cement.

The outer ends 22^a of the members 22 extend into the space between the two sections 11^a and 11^b, but preferably extend short of the section 11^b to permit of the free circulation of air around the ends of the plates. The outer ends of the members 22 which are located next to the bonding tiles 11^c are preferably bent away from the same, as at 22^b, 70 in order to permit of the circulation of air 75 around the ends of those members.

Preferably, the side walls are made in substantially the same manner as the rear wall; that is to say, the side walls are formed with spaced sections which are connected by the 80 bonding tiles 11^c, as indicated in dotted lines, thus forming a plurality of ducts between the sections. The members 22 also preferably extend around the sides of the furnace, as also indicated in dotted lines. The front wall is 85 also preferably provided with bonding tiles and cooling plates as illustrated.

Preferably, air is introduced into the space between the sections 11^a and 11^b of the rear wall, and in the form illustrated, a blower 24 90 is used for forcing a blast of air into the said spaces. The blower leads to a conduit or manifold 25, to which are connected branch pipes or ducts 26, leading to the respective spaces between the sections 11^a and 11^b of the rear wall, which are located between the successive bonding tiles 11^c. The air flows through the spaces between the sections of the rear wall and between the sections of the side walls, the same flowing over the free outer 95 100

ends 22^a and 22^b of the members 22, and absorbing heat therefrom, and flows around to the front of the furnace into the space 27, between the front wall 10 and the casing 21 and through suitable openings 28, into the front of the furnace where it is mixed with the powdered fuel entering the furnace from the nozzle 13.

The members 22 being formed of a material which is a much better conductor of heat than are the refractory members of which the wall is principally formed, conduct the heat from the furnace side of the wall into the space between the sections 11^a and 11^b where the air impinges against the outer ends 22^a and 22^b of the members and absorb the heat therefrom, the heat so absorbed being utilized to raise the temperature of the entering air. At the same time, by carrying the heat away from the inner face of the wall or walls, they are maintained at a sufficiently low temperature greatly to increase the life of the wall. The air entering through the openings 28 in the front wall 10 also lowers the temperature of the front wall and increases the life thereof. Better economy can be secured due to the higher furnace temperatures which may be used without increased service on the furnace walls.

30 I claim:

1. In a furnace, a wall made in sections spaced apart, both sections being made of material of low heat conductivity, members of good heat conducting material as compared to the material of said sections placed in the inside section with their inner edges spaced from the inside face of said section and their other edges extending into the space between the sections.

40 2. In a furnace, a wall made in sections spaced apart with bonding tile extending across the space and constituting a portion of each wall section, both sections being made of material of low heat conductivity, members of good heat conducting material as compared to the material of said sections placed in the inside section with their inner edges spaced from the inside face of said section and their other edges extending into the space between the sections.

50 3. In a furnace, a wall made in sections spaced apart, both sections being made of material of low heat conductivity, thin metal plates in the inner section extending into the space between the sections, and means protecting the inner edges of said plates from the heat of the furnace.

60 4. In a furnace, a wall made in sections spaced apart, both sections being made of material of low heat conductivity, and thin metal plates in the inner section extending into the space between the sections, said sections being connected at intervals by bonding tile extending across said space and constituting a part of each section.

5. In a furnace, a wall made in sections spaced apart, both sections being made of material of low heat conductivity, and thin metal plates in the inner section extending into the space between the sections, said sections being connected at intervals by bonding tile extending across said space and constituting a part of each section, some metal plates being bent away from said tile in said space.

6. In a furnace, a wall made in sections spaced apart, both sections being made of material of low heat conductivity, tile extending between said sections to divide the space between said sections into a plurality of ducts, members of good heat conducting material as compared to the material of said sections placed in the inside section with their inner edges spaced from the inside face of said section and their other edges extending into the space between the sections.

7. In a furnace, a wall made in sections spaced apart, both sections being made of material of low heat conductivity, tile extending between said sections to divide the space between said sections into a plurality of ducts, members of good heat conducting material as compared to the material of said sections placed in the inside section with their inner edges spaced from the inside face of said section and their other edges extending into the ducts between the sections.

8. In a furnace, a wall made in sections spaced apart, both sections being made of material of low heat conductivity, metal plates disposed in the inner section and extending into the space between the sections, and means protecting the inner edges of said plates from the heat of the furnace.

9. In a furnace, a wall of refractory material, both sections being made of refractory material, said wall being made in sections spaced apart, tile extending between said sections to divide the space between said sections into a plurality of ducts, and members of good heat conducting material as compared to the refractory material placed in the inside section with their outer edges extending into the ducts between the sections.

10. In a furnace, a wall of refractory material made in two sections spaced apart, both sections being made of material of low heat conductivity, a plurality of ducts formed in the space between said sections, means for causing passage of air through said ducts, and members of relatively good heat conducting material disposed in said inner sections and extending into said ducts.

11. In a furnace, a wall of refractory material made in two sections spaced apart, both sections being made of material of low heat conductivity, a plurality of ducts formed in the space between said sections, means for causing passage of air through said ducts, and members of relatively good heat conducting material disposed in said inner sections

and extending into said ducts, and means protecting the inner edges of said members from the heat of the furnace.

12. In a furnace, a wall made in two sections spaced apart, both sections being formed of refractory blocks, horizontally disposed metal plates between said blocks and extending into the space between said sections, and means protecting the inner edges of said plates from the heat of the furnace.

JAMES C. HOBBS.
